UNITED STATES PATENT OFFICE.

WITMER J. KENDIG, OF LANCASTER, PENNSYLVANIA, ASSIGNOR OF ONE-FOURTH TO
CHRISTIAN H. KENDIG, OF READING, PENNSYLVANIA.

SEWING-MACHINE NEEDLE.

1,333,259.

Specification of Letters Patent.

Patented Mar. 9, 1920.

Application filed January 24, 1919. Serial No. 272,813.

To all whom it may concern:

Be it known that I, WITMER J. KENDIG, a citizen of the United States, residing at Lancaster, in the county of Lancaster and 5 State of Pennsylvania, have invented certain new and useful Improvements in Sewing-Machine Needles, of which the following is a specification.

This invention relates to improvements in 10 sewing machine needles and the object is to provide a needle into which the thread may be inserted with ease.

The invention consists in forming a hollow needle from a strip of metal, bent to 15 substantially tubular form, and having a longitudinal slot in the sewing end thereof, with a thread engaging ear at one end of the slot and an eye at the opposite or lower end and in close proximity to the point of 20 the needle.

The invention represents a step forward in the art as disclosed in United States Letters Patent No. 1,073,140, issued to me under date of September 16th, 1913.

25 As compared with the device disclosed in said patent, my present invention is more simple in construction and it especially provides for overcoming one objectionable feature, namely, the tendency to shear off the 30 thread while in operation.

The invention is more fully described in the following specification and clearly illustrated in the accompanying drawing, in which:—

35 Figure 1 represents the blank strip of metal from which the needle is to be formed.

Fig. 2 represents the needle, formed by turning said sheet into tubular form.

40 Fig. 3 represents a side view of a portion of the needle, at the juncture of the larger and smaller diameters, and showing the thread engaging ear at one side.

Fig. 4 represents, in exaggerated form, a cross-section of the needle taken through 45 4—4 of Fig. 2.

Fig. 5 is an elevational view of the portion shown in Fig. 4, with the thread resting in the slot.

50 The numeral 1 designates a blank or strip of metal, the upper portion of which is considerably wider than the lower portion. At the point where the wider portion merges into the narrower portion, I form an ear 2 by cutting a slot 3 into the sheet.

55 The lower extremity of the sheet, that is, the end of the narrow portion, is cut to a

point 4 and immediately above the point where this point formation begins, I cut a substantially semi-circular indentation 5 in the longitudinal edge, at the side opposite 60 that in which the slot 3 is cut.

This blank forms the entire body from which the finished needle is made.

The blank is turned into substantially tubular form, as shown in Fig. 2, the upper 65 portion forming a body of larger diameter than the lower portion.

In the upper portion, the meeting longitudinal edges abut, as shown at 6, while the lower portion of the needle, that is, the 70 sewing portion, has one longitudinal edge overlapping the other, 7 representing the outer or overlapping edge and 8 the inner edge, thus forming an elongated slot 9.

The ear 2, by which the thread is engaged 75 while inserting it into the needle, is bent, as shown in Fig. 3, to form a spring or snap device to prevent the thread from disengaging itself after it has been inserted.

The eye 5, in the lower extremity of the 80 needle, is partially closed by the overlapping edge 7, and the meeting edges at the lower extremity are rolled into a point 10.

In inserting the thread, it is drawn under the ear 2 and then pulled down along the 85 needle body, passing through the slot 9 and into the hollow interior of the needle, until the eye 5 is reached, where it passes out.

During the act of sewing, while the needle moves vertically through the cloth, the 90 thread beyond the eye is carried along with the needle, and to insure against the thread being sheared off by the cloth, I provide this longitudinal slot 9, into which the thread 11 is forced, and where it lies, protected from 95 contact with the cloth, as clearly shown in Figs. 4 and 5.

The construction of the needle is extremely simple, and this tendency to shear off the thread is entirely overcome.

Having thus described my invention, I 100 claim:—

1. A hollow sewing machine needle, whose cross section is substantially circular, one end of which is reduced in diameter and 110 formed with a longitudinal slot terminating in an eye, one edge of the metal along the slot being spaced from the other and overlapping it, to form a longitudinal opening or slot, and a thread engaging ear at the 105 other end.

2. A hollow sewing machine needle pro-

vided with an eye near the pointed end, slotted from the top to the eye thereby providing adjacent edge portions and including an upper portion of circular cross-section 5 whose longitudinal edges abut, and a thread engaging ear formed at the lower extremity of said abutting edges, and a lower portion whose longitudinal edges overlap each other

and are spaced apart to form a longitudinal slot.

10

In testimony whereof I affix my signature.

WITMER J. KENDIG.
